UNITED STATES PATENT OFFICE.

FREDERICK P. WOOD, OF NEW YORK, N. Y., ASSIGNOR TO AMERICAN CAN COMPANY, OF NEW YORK, N. Y., A CORPORATION OF NEW JERSEY.

MOISTUREPROOF CONTAINER.

Application filed April 18, 1919. Serial No. 290,928.

To all whom it may concern:

Be it known that I, FREDERICK P. Wood, a citizen of the United States, residing in New York, in the county of New York and 5 State of New York, have invented a new and useful Improvement in Moistureproof Containers, of which the following is a specification.

This invention relates in general to moisture proof containers and has for its object broadly the provision of a completely moisture proof container of simple and readily manufactured construction.

Numerous other objects and advantages 15 of the invention will be apparent as it is better understood from the following description when considered in connection with the accompanying drawing illustrating a preferred embodiment thereof.

20 Referring to the drawing,

Figure 1 is a partial perspective of a can or container embodying my present invention.

Fig. 2 is a vertical partial section there 25 through, and

Fig. 3 is an enlarged detailed similar view.

Upon the drawing I have shown a can body wall of fibrous material and composed of an internal carcass 11 consisting of two 30 layers of fiber board or paper 12 connected together by any suitable cement, glue being sufficient, although fusible cement may be used if desired. Another fibrous layer 14 is provided upon the outside of the body and 35 is cemented thereto by an interposed layer 15 of fused cement, asphaltum being well adapted for the purpose. The cover in the present instance consists of a metal body or sheet 16 pressed outwardly at 17 to form 40 a shoulder 18 fitting within the top of the body. Beyond the shoulder 18, the cover extends outwardly at 19 over the end wall of the body and thence downwardly at 20 in a cylindrical flange adapted to lie against 45 the outer face of the body. The edge 21 of the flange 20 is left as it is formed by the punching or press work in constructing

the body and is bent inward slightly at 22 and forced to cut or otherwise enter through the outer fiber layer 14 and to extend into 50 or at least into contact with the layer of fused cement 15.

The fused cement forms an absolutely moisture proof layer in the body and the tin or other sheet metal cover is also of 55 course moisture proof. The contacting of the two therefore produces a complete encasement of the contents within the can and also of the inner fiber layer or carcass 11 so that there is no chance for moisture to 60 enter into the can.

It is thought that the invention and many 65 of its attendant advantages will be understood from the foregoing description, and it will be apparent that various changes may be made in the form, construction and arrangement of the parts without departing from the spirit and scope of the invention or sacrificing all of its material advantages, 70 the form hereinbefore described being merely a preferred embodiment thereof.

I claim:

A moisture-proof container formed of a laminated paper body and having metal ends, laminations of said body being connected together by a continuous film of non-porous fused cement and the said metal ends having shoulders arranged within the ends of the laminated body from which the metal extends up and over to the outside thereof, the edges of said ends being forced through the outer fiber lamination and into contact with the said film of cement, whereby said ends are joined to said film with impervious connections, the whole forming a package comprising a continuous impervious enclosure of cement and metal. 75

Signed in the presence of two subscribing witnesses.

FREDERICK P. WOOD.
